UNITED STATES PATENT OFFICE.

CHARLES JOHN ELLIOTT, OF OXNARD, CALIFORNIA.

GUARD FOR TELEPHONE AND TELEGRAPH WIRES.

1,005,179.

Specification of Letters Patent. Patented Oct. 10, 1911.

Application filed July 11, 1910. Serial No. 571,432.

To all whom it may concern:

Be it known that I, CHARLES J. ELLIOTT, a citizen of the United States, residing at Oxnard, in the county of Ventura and State 5 of California, have invented a new and useful Guard for Telephone and Telegraph Wires, of which the following is a specification.

In a previous patent of mine No. 928,431, 10 July 20, 1909, I have shown a device adapted to be applied to poles or supports for wires carrying a high tension current at places where such high tension wires are strung in the air above and across telegraph or telephone wires, as, for example, along the line of a railway or any telegraph or telephone line, roadway or building which would be damaged or rendered unsafe if the high tension wires above were to break and fall upon 15 them, the device acting to sever that section of the broken wire from its line so that it could not hang in the air from its unbroken end and damage underlying wires, buildings or other objects. In that patent the device 20 acted by grounding the section of broken wire, causing it to be severed by being burned off, and the object of the present invention is to accomplish the same result without employing the ground connection and to cause 25 the broken section to be placed in electrical connection with an adjacent wire of the same line, thus forming a metallic circuit through the guard which will cause it to burn off the broken section when the latter comes in contact with the guard.

Another advantage of the present invention is that considerable economy is attained by the elimination of the ground connection employed in the previous patent.

Referring to the drawings: Figure 1 is a 40 perspective view of the upper portion of a pole and support for the high tension wires, showing the guard as applied thereto. Fig. 2 is a perspective view of a line of railway 45 which is paralleled by a telegraph or telephone line, and illustrating the same, overhead high tension wires which are strung across the railway above the telegraph and telephone wires, the posts supporting the 50 high tension wires being equipped with the guards forming the invention. Fig. 3 is a sectional view through one of the guard-arm insulator supports on line x^3-x^3 Fig. 4. Fig. 4 is a section transverse to the section 55 shown in Fig. 3, on line x^4-x^4 Fig. 3.

1 designates a line of railway which is

paralleled by telegraph wires 2 carried on poles 3. Obviously, the wires 2 need not necessarily be wires extending along the side of a railway, as they might be telephone or 60 telegraph wires which extend along a thoroughfare or even outlying districts. The wires 2 are the wires which are to be protected from any damage which might be caused by breaking of the high tension wires 65 4 which lie above the wires 2 and are supported in the usual manner by insulators 5 on cross arms 6 carried by poles 7.

The guard comprises a ring 8 supported by arms 9 so that it surrounds the wire 4 70 which it is to guard, the arms 9 being supported in any desired manner upon the cross arm 6, as for example, by the insulating device shown in Figs. 3 and 4 comprising a block 10 which rests upon the cross arm 6, the 75 block 10 being notched transversely of the cross arm, as shown in Fig. 4, to receive the arm 9, and a block 11 rests on top of the arm 9 and partially within the notched block 10, as shown in Fig. 4, a U-bolt 12 passing 80 over the upper block 11 and through the cross arm 6 securely holding the parts together. The arms 9 are given an upward inclination, as shown; so as to bring the guard ring 8 substantially concentric with 85 the wire 4. The guard 8 may be made of gas pipe in three sections a , b and c , the section a being connected by T's 13 with sections c and b , the sections c and b being connected by a union 14. The arms 9 are connected to the T's 13. The union 14 enables 90 the guard to be connected to the arms 9 and then moved up into position from below the wire 4, the wire 4 passing between the sections c and b , the union 14 being removed. 95 After the guard is in place with the wire 4 in the center thereof, the union 14 may secure the two sections c and b together, the arms 9 being secured to the cross arm 6 by the insulating device described.

Fig. 1 shows the arrangement for a three phase system and a single phase system, two wires being shown on one side of the pole and three wires on the other. In the three phase system the guard 8 is electrically connected with middle wire 4 a by a wire 15, and guard 8 a is electrically connected with wire 4 b by wire 16, and guard 8 b is electrically connected with wire 4 a by wire 17 which is shown as extending to wire 15. Thus all 110 three guards are normally alive, and it is obvious that should one of the wires 4 break

at a point between the two poles on opposite sides of the railway, shown in Fig. 2, the broken wire will drop into contact with one or both guards through which it passes and upon striking the guard will be immediately severed by the arc, which will result on account of the poor contact of the wire with the guard, so that the severed section will fall immediately to the ground without damage, as it is dead.

I prefer to construct the guards so that they completely encircle the wire, because generally when one of the high tension wires breaks, say, for example, near one of the insulators, its first movement is an upward and backward snap or whipping action due to the action from its mechanical tension, which upward swing brings it into contact with the upper part of the guard ring causing it to be immediately severed. If in its upward swing the wire did not move high enough to touch the upper part of the guard ring, its next movement will be downward and it will strike the bottom part of the guard ring instead and will thereupon be severed and fall to the ground. Thus when one of the high tension wires breaks it must necessarily strike its guard ring, as the

guard completely surrounds it, and it is thus sure to be severed. On the other side of the cross arm I have shown the two guards electrically connected with the opposite wires 4 by wires 18 and 19, so that both guards are normally charged. Thus if the wire 4^c breaks, its guard 8^c which is charged by wire 19 from wire 4^c will sever the wire 4^c. In order to enable linemen to safely approach the cross arm 6, I provide switches 20 in the respective wires 15, 16, 17, 18 and 19 which may be opened when it is desired to cut out the guards.

What I claim is:—

In combination with high tension wires forming a metallic circuit for electrical transmission, a guard surrounding each wire and electrically connected with another of said wires of different potential from the one it surrounds.

In testimony whereof, I have hereunto set my hand at Oxnard, California, this 30th day of June, 1910.

CHARLES JOHN ELLIOTT.
